MEASURING DEVICE

Norman H. Bolz, Euclid, Ohio, assignor to Patterson-Leitch Company, Cleveland, Ohio, a corporation of Ohio

Application January 10, 1939, Serial No. 250,206

16 Claims. (Cl. 164—59)

The present invention relates to a device for predeterminately measuring lengths to be operated upon or, alternately cut off from stock pieces of light material or heavy, cumbersome materials such as metal beams, bars, shapes and sheets, and similar types of stock material of non-metallic composition such as various kinds of lumber and the like. Heretofore, in the operation of cut-off machines, such as power shears, saws, abrasive cut-off wheels, rotary cutters, etc., operating upon heavy stock materials of the type already indicated, it has been the practice to run the length of stock through the machine and out onto a supporting table until its end abuts against a length gauge in the form of a block or plate member previously located the desired distance from the cutting point of the machine and fastened in place by the operator. When a large number of different lengths of such stock are to be cut, such lengths varying from only a few feet to possibly over 100 feet, a substantial portion of the operator's time and labor has been occupied with the locating and fastening of the length abutment plate or feed gauge. And very often the use of such a feed gauge has been dispensed with by the operator, due to the inconvenience and time consumed in its manipulation, the operator relying merely upon a chalk, pencil or scribed mark measured off upon the length of stock to determine the cut-off point. As a result, the human element entered into the cut-off operation in the alignment of the cut-off mark with the cutting point of the machine, with a corresponding factor of error lessening the uniformity and accuracy of the work.

Accordingly, the general object and nature of the present invention is to minimize the above enumerated difficulties and to provide means for rapidly and accurately locating a cut-off length abutment member at any desired point and over a wide range of lengths, such device being controlled and operated by the operator of the cut-off machine without requiring him to leave his customary position at the latter. Briefly outlined, the device embodying the principle of my invention comprises an electric power driven carriage or vehicle having an abutment plate adapted to project over the stock supporting table, and attached to an endless measuring tape passing around an indicating point located on the cut-off machine. An electric control switch for actuating the drive motor of such vehicle or carriage is also located at the cut-off machine, and enables the operator to easily control the movements or pre-location of the carriage and its attached abut-

ment plate without leaving his customary position at the cut-off machine. There is also provided an intermittent signalling means such as an electric light or bell which indicates the unit distances travelled by the carriage, so that the operator's close attention to the readings upon the measuring tape is not required, when the carriage is moving at full speed over a substantial distance.

10 The invention has been and will be described with respect to a cut-off machine but it is obvious that it is applicable to a wide variety of machines or tools and it will be understood that a cut-off machine has been used merely as an example.

15 It is also to be understood that the invention is not to be restricted to a cut-off machine.

To the accomplishment of the foregoing and related ends, said invention, then, consists of the means hereinafter fully described and particularly pointed out in the claims.

20 The annexed drawing and the following description set forth in detail certain mechanism embodying the invention, such disclosed means constituting, however, but one of various mechanical forms in which the principle of the invention may be used.

In said annexed drawing—

25 Fig. 1 is a general elevational view of a stock cut-off machine and supporting table with the device embodying my invention assembled therewith; Fig. 2 is an enlarged, detail side elevational view of the abutment plate carriage; Fig. 3 is an end elevational view of the same, taken upon a plane normal to that of Fig. 2 and substantially along line 3—3 as indicated in Fig. 1; Fig. 4 is an elevational view of the carriage taken upon the side opposite to that of Fig. 2; Fig. 5 is a detail view of the measuring tape supporting roller at the end removed from the cut-off machine;

40 Fig. 6 is a wiring diagram of the carriage drive motor circuit; and Figure 7 is a detail view of part of the measuring tape.

45 Referring more particularly to the drawing and especially Fig. 1 thereof, the numeral 1 indicates generally any tool or a cut-off machine such as a power shear adapted to operate upon a piece of stock material 2 such as a steel beam or bar. The stock material 2 extends out through the cut-off machine 1 onto the top of the supporting table 3, which customarily has a series of spaced rollers 4 to facilitate the movement of the heavy stock thereover. A trackway 5 is positioned above the stock supporting table 3. In the illustrative embodiment, the trackway 5 consists essentially of an I-beam supported at one end at the cut-off

machine 1 and at the other end by the vertical upright 6 extending upwardly from the end of the supporting table 3.

A power driven carriage or vehicle, indicated generally at 7, carries an abutment plate 21 which projects downwardly above the top of the supporting table 3 and against which the end of the length of stock material 2 is adapted to abut. An endless measuring tape 9 is connected to the carriage 7 and passes around a supporting roller 10 mounted on the front of the cut-off machine 1. A fixed pointer 11 mounted adjacent the roller 10 indicates the readings upon the tape 9 and correspondingly, the distance of the carriage 7 and its abutment plate 21 from the cut-off point of the machine 1 and operates as the means for allowing the operator to control the movement of the carriage 7 over the trackway 5. An electric signal 13, such as an electric light or bell is also mounted on the cut-off machine 1 and is so electrically connected as to be intermittently actuated by the movement of the carriage 7 during its travel.

Now directing attention to Figs. 2, 3 and 4, the carriage 7 comprises a framework having the bottom plate 15 and the two end uprights 16 and 17 which join the bottom plate 15 to the upper slide plate 18. The slide plate 18 is carried in a groove or slideway formed by the spacer bars 19 and the overlying bars 20, both secured to the under side of the bottom flange of the trackway 5. An abutment plate 21 projects downwardly from one end of the carriage 7, being secured to the upright 16 and is adapted to contact with and abut the end of the length of stock material 2. An electric motor 22 is mounted upon the base plate 15 of the carriage 7, and is connected through the chain 23 and sprocket 24 to the drive shaft 25 of the reduction gear unit 26. The driven shaft 27 of the reduction gear unit 26 carries a pinion 28 which meshes with the gear rack 29. The gear rack 29 in turn is supported by means of the angle bars 30 located at spaced intervals along the trackway 5 and attached at their upper ends to the top flange of the trackway 5.

A series of bus bars 31, 32 and 33 are also carried upon the intermediate portion of the angle bars 30 by means of insulating mountings 34, 35 and 36 respectively. Trolley rollers 37, 38 and 39 are mounted upon the upright pole or rod 40 which is carried at its lower end upon the base plate 15 of the carriage 7. The trolley rollers 37, 38 and 39 of course are connected by electrical wires or conduits to the electric drive motor 22.

An electric motor brake 41, actuated by the solenoid 42 is also mounted on the outer end of the shaft of the motor 22.

An upright 43, mounted upon the base plate 15 of the carriage 7 is attached at its upper end to the endless measuring tape 9. Another upright 44, similarly mounted, carries at its upper end the contact shoe 45 which is yieldably mounted by means of the bar 46 telescoping in the interior of the upright, and the compression spring 47. As will best be seen from Fig. 3, the contact shoe 45 is adapted to bridge the contact points 48 and 49 mounted upon an insulating block 50 secured to the upper flange of the trackway 5. Electric wires, such as indicated at 51, connect the contact points 48 and 49 in series to a source of electric power and to the signal 13. These contact points 48 and 49 are preferably located at unit distances 1 foot apart. Thus, as the carriage 7 travels along the trackway 5, the bridging of the contacts 48 and 49 by the contact shoe 45 will in-

termittently cause the electric signal 13 to be actuated, so that the operator, merely by counting the number of signal impulses, can determine the number of feet which the carriage has travelled.

Referring to Fig. 5, the endless measuring tape 9 passes around a pulley 55 on the right hand or outer end of the trackway 5. The pulley 55 in turn is carried by the two bars 56 and 57 which are spring mounted in the casings 58 and 59 respectively and against the action of the compression springs 60 and 61. In this manner, a uniform tension upon the measuring tape 9 is assured.

15 The electric circuit of the control switch 12 and drive motor 22 is illustrated in the wiring diagram of Fig. 6, where the electrical power passes through the control switch 12 to the bus bars or trolley lines 31, 32 and 33, thence to the 20 motor 22. The solenoid 42 is connected in series with the motor 22, so that it operates to release the brake 41 when current is supplied to the motor 22, and conversely to apply the brake 41 when the current is shut off.

25 In order to obtain a sufficient flexibility of speed operation of the electric drive motor 22, I have provided an especially constructed electric motor which is capable of "inch" operation as well as relatively high speed operation. By the 30 term "inching" I mean the ability of the operator to momentarily throw the control switch one way or the other and thereby obtain a very slight movement of the carriage 7, such as a fraction of an inch. The high speed operation of the electric motor is desired in order to secure a rapid 35 travel of the carriage 7 when it was moved relatively large distances, such as several feet. Accordingly, an electric motor of the low temperature operating, large current capacity type is 40 particularly suitable to obtain such flexibility of operating ranges. A three-phase reversing induction motor, with a 440 volt field capacity and operated on a 220 volt line is cited as a specific example of an electric motor meeting these 45 requirements.

Other modes of applying the principle of my invention may be employed instead of the one explained, change being made as regards the mechanism herein disclosed, provided the means 50 stated by any of the following claims or the equivalent of such stated means be employed.

I therefore particularly point out and distinctly claim as my invention:

1. In a measuring device for a machine operating on material, including cutting off, means for supporting the length of stock to be cut off, a railway mounted in spaced relation and parallel to said supporting means, a power actuated vehicle traversible on said railway, and an abutment plate carried by said vehicle and being suspended above said supporting means, said abutment plate being adapted to abut the end of such lengths of stock, means on said vehicle to stop the same precisely, and a switch on said machine to control such means; the power actuating means for the vehicle being mounted on the vehicle.

2. In a measuring device for a tool, means for supporting the length of stock to be operated upon by said tool, a railway mounted in spaced relation and parallel to said supporting means, a vehicle traversible on said railway, an abutment plate carried by said vehicle and projecting above said supporting means, said abutment plate being adapted to abut the end of such lengths of stock,

SHEETS & BARS,

3

power means carried by said vehicle for driving the latter along said railway and a switch electrically connected to said power means, said switch being located at the operator's station at said tool.

3. In a measuring device for a tool, means for supporting the length of stock to be operated upon by said tool, a railway mounted in spaced relation and parallel to said supporting means, a vehicle traversible on said railway, an abutment plate carried by said vehicle and projecting above said supporting means, said abutment plate being adapted to abut the end of such lengths of stock, an electric motor mounted on said vehicle, drive transmitting means connecting said motor to said railway, electric power transmitting means associated with said railway and connected to said motor, and control means for delivering electric power to said transmission means, said control means being located at the operator's station at said tool.

4. In a measuring device for a cut-off machine, means for supporting the length of stock to be cut off, a railway mounted in spaced relation and parallel to said supporting means, a vehicle traversible on said railway and supported entirely thereby, an abutment plate carried by said vehicle and projecting above said supporting means, said abutment plate being adapted to abut the end of such lengths of stock, and an endless measuring tape supported at one end at said cut-off machine and at the other end at the end of said railway, said vehicle being so connected to said tape and the markings of the latter being so arranged as to indicate at its end supported at said cut-off machine the amount of said lengths of stock.

5. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, power means carried by said vehicle for driving the latter along said railway, and an endless measuring tape supported at one end at said cut-off machine and at the other end at the end of said railway, said vehicle being so connected to said tape and the markings of the latter being so arranged as to indicate at its end supported at said cut-off machine the amount of said lengths of stock and means to stop said vehicle an unlimited number of times and in an unlimited number of positions.

6. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, an electric motor mounted on said vehicle, drive transmitting means connecting said motor to said railway, electric power transmitting means associated with said railway and connected to said motor, control means for delivering electric power to said transmission means, said control means being located at the operator's position of said cut-off machine, and an endless measuring tape supported at one end at said cut-off machine and at the other end at the end of said railway, said vehicle being so

connected to said tape and the markings of the latter being so arranged as to indicate at its end supported at said cut-off machine the amount of said lengths of stock.

5. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, power means carried by said vehicle for driving the latter along said railway, an endless measuring tape supported at one end at said cut-off machine and at the other end at the end of said railway, said vehicle being so connected to said tape and the markings of the latter being so arranged as to indicate at its end supported at said cut-off machine the amount of said lengths of stock, and intermittent signal means actuated by movement of said vehicle so constructed as to visibly or audibly signal unit distances of travel of said vehicle.

8. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, an electric motor mounted on said vehicle, drive transmitting means connecting said motor to said railway, electric power transmitting means associated with said railway and connected to said motor, control means for delivering electric power to said transmission means, said control means being located at the operator's position of said cut-off machine, an endless measuring tape supported at one end at said cut-off machine and at the other end at the end of said railway, said vehicle being so connected to said tape and the markings of the latter being so arranged as to indicate at its end supported at said cut-off machine the amount of said lengths of stock, and intermittent signal means actuated by movement of said vehicle so constructed as to visibly or audibly signal unit distances of travel of said vehicle.

9. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, power means carried by said vehicle for driving the latter along said railway, an endless measuring tape supported at one end at said cut-off machine and at the other end at the end of said railway, said vehicle being so connected to said tape and the markings of the latter being so arranged as to indicate at its end supported at said cut-off machine the amount of said lengths of stock, an electric signal located at said cut-off machine, a series of electric switches mounted at unit distances along said railway, an electric circuit connecting said switches to said signal, and contact means carried by said vehicle for actuating said switches.

10. In a measuring device for a cut-off machine, means for supporting the length of stock to be cut off, a railway mounted in spaced rela-

tion and parallel to said supporting means, a vehicle traversible on said railway, an abutment plate carried by said vehicle and projecting above said supporting means, said abutment plate being adapted to abut the end of such lengths of stock, a low temperature operating, relatively large current capacity electric motor mounted on said vehicle, drive transmitting means connecting said motor to said railway, electric power transmitting means associated with said railway and connected to said motor, and control means for delivering electric power to said transmission means, said control means being located at the operator's station at said cut-off machine.

11. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, a low temperature operating, relatively large current capacity electric motor mounted on said vehicle, drive transmitting means connecting said motor to said railway, electric power transmitting means associated with said railway and connected to said motor, control means for delivering electric power to said transmission means, said control means being located at the operator's position of said cut-off machine, and an endless measuring tape supported at one end at said cut-off machine and at the other end at the end of said railway, said vehicle being so connected to said tape and the markings of the latter being so arranged as to indicate at its end supported at said cut-off machine the amount of said lengths of stock.

12. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, an electric motor mounted on said vehicle, drive transmitting means connecting said motor to said railway, electric power transmitting means associated with said railway and connected to said motor, control means for delivering electric power to said transmission means, said control means being located at the operator's position of said cut-off machine, an endless measuring tape supported at one end at said cut-off machine and at the other end at the end of said railway, said vehicle being so connected to said tape and the markings of the latter being so arranged as to indicate at its end supported at said

cut-off machine the amount of said lengths of stock, an electric signal located at said cut-off machine, a series of electric switches mounted at unit distances along said railway, an electric circuit connecting said switches to said signal, and contact means carried by said vehicle for actuating said switches.

13. In a measuring device for a cut-off machine, means for supporting the length of stock to be cut off, a railway mounted in spaced relation and parallel to said supporting means, a vehicle traversible on said railway, an abutment plate carried by said vehicle and projecting above said supporting means, said abutment plate being adapted to abut the end of such lengths of stock, an electric motor mounted on said vehicle, a gear rack carried by said railway, a gear driven by said motor and engaging with said rack, an electric trolley line also carried by said railway and connected to said motor, a control switch for said trolley line located at the operator's position of said cut-off machine, an endless measuring tape supported at one end at said cut-off machine and at the other end at the end of said railway, said vehicle being so connected to said tape and the markings of the latter being so arranged as to indicate at its end supported at said cut-off machine the amount of said lengths of stock, an electric signal located at said cut-off machine, a series of electric switches mounted at unit distances along said railway, an electric circuit connecting said switches to said signal, and contact means carried by said vehicle for actuating said switches.

14. A measuring device for a cut-off machine comprising an abutment plate, a vehicle, a motor and a brake, said plate, brake and motor being carried by said vehicle, there being means present, at the operator's position of said cut-off machine, to energize said motor and to apply said brake, respectively.

15. A measuring device for a cut-off machine comprising an abutment plate, a vehicle, a motor and a brake, said plate, brake and motor being carried by said vehicle, there being means present, at the operator's position of said cut-off machine, to energize said motor and to apply said brake, respectively, and means on said vehicle whereby said brake is applied when said motor is de-energized.

16. In a measuring device for a cut-off machine, a movable abutment plate, means to move said plate at high speeds, means to move said plate at low speeds, and means to stop said plate positively and accurately where desired, said last named means being totally mechanical in operation and all of said means moving with said abutment plate.

NORMAN H. BOLZ.
